UNITED STATES PATENT OFFICE.

FREDERICK C. KROEGER, OF ANDERSON, INDIANA, ASSIGNOR, BY MESNE ASSIGNMENTS, TO DELCO-REMY CORPORATION, OF DAYTON, OHIO, A CORPORATION OF DELAWARE.

IGNITION APPARATUS.

Application filed March 12, 1924. Serial No. 698,582.

This invention relates to electrical ignition apparatus for internal combustion engines of the type including an ignition timer and distributor unit driven by the engine, the 5 timer housing having a shank concentric with the timer shaft adapting it to be received by a tubular part or socket provided in the engine frame or in an accessory operated by the engine.

10 One object of the invention is to provide for holding the ignition timer upon its support and to provide for adjusting the timer with respect to its driving means so that the ignition may be advanced or retarded. This 15 object is accomplished by forming from sheet metal a clamp adapted to adjustably grip the shank of the timer housing, and by forming one or more arms extending from the shank. One of these arms may cooperate with means for preventing endwise movement of the timer, and the other may be connected with the spark lever on the steering column of the automobile for angularly adjusting the timer.

20 25 Further objects and advantages of the present invention will be apparent from the following description, reference being had to the accompanying drawing wherein a preferred embodiment of one form of the present invention is clearly shown.

In the drawings:

Fig. 1 is an elevation of an ignition timer supported by a machine frame, a fragment of which is shown, and a sectional view of 30 a clamp embodying the present invention applied to the timer.

Fig. 2 is a sectional view of the timer on line 2—2 of Fig. 1, and a plan view of the clamp.

40 Fig. 3 is a sectional view on line 3—3 of Fig. 2.

Referring to the drawings, the timer and distributor unit, hereafter called the "timer", is designated by numeral 20 and includes a 45 cup-shaped housing 21 having a shank 22 which includes a clamp receiving portion 23 and a portion 24 reduced in diameter adapted to be received by a socket in a machine frame 25, the frame 50 providing a bearing rotatably supporting the shank portion 24. The frame 25 carries an engine driven shaft 26 connected by spiral gears 27 and 28 with the timer shaft 29.

The timer clamp designated as a whole

by numeral 30 is provided with an aperture 55 slightly greater in diameter than the shank portion 23, and with spaced arms 31 and 32, the ends of which are bent around to form substantially tubular portions 33 and 34 respectively, which receive a clamping screw 60 35 cooperating with a clamping nut 36. The sheet material from which the clamp is constructed is less in thickness than the width of shank portion 23; and from the main portion of the material surrounding the shank portion 23, a plurality of lugs or teeth 65 37 are struck out to provide clamping grips which bite into the material of the shank portion 23 when the arms 31 and 32 are tightened about portion 23. It is apparent 70 that the material is relatively narrow between the lines X—X and Y—Y in Fig. 2, so that the arm 32 may yield slightly relative to the main portion of the clamp.

In order to prevent endwise movement of 75 the timer and clamp while permitting rotation thereof, the clamp is provided with an arm 40 having a slot 41 which receives a hold-down screw 42 engaging a tapped lug 43 provided by frame 25. Under the head of screw 42 there is located a spring 44 bearing against a hold-down washer 45 resting upon the arm 40. In this way the arm 40 is yieldingly held against the lug 43 and the shank portion 23 yieldingly against the 80 supporting frame 25.

To turn the timer housing 21, the clamp 30 is provided with an arm 50 which is apertured to receive the end 51 of a link 52 connected in any suitable manner with the 90 spark control lever of the automobile. A washer 53 and pin 54 serve to hold the link 52 in place.

To adjust the timer relative to the spark control lever, the clamping screw is loosened 95 to permit relative movement of the timer and clamp. The spark lever is adjusted to a desired position, for example, full retard. The timer is turned while the clamp remains fixed until the ignition is timed for a fully 100 retarded spark. Then the clamping arms 31 and 32 are tightened about the timer shank. The timer is then connected for manipulation through the link 52 and arm 50.

If the timer is not manually controlled, 105 link 52 is, of course, omitted. The spring 44 is omitted between the screw head 42 and washer 45, so that the arm 40 may be

clamped in the desired position with respect to the supporting frame 25. Generally where manual control of spark timing is not used, the timer includes a speed responsive device for automatically controlling the spark.

While the form of embodiment of the invention as herein disclosed, constitutes a preferred form, it is to be understood that other forms might be adopted, all coming within the scope of the claims which follow.

What is claimed is as follows:

1. A clamp for securing an operating member to the shank of an ignition timer, and comprising a relatively thin, flat member having an aperture for receiving the shank, and clamping arms including aligned tubular portions spaced by a notch extending to said aperture, the clamping arms being substantially greater in width of cross section near the tubular portions than portions adjacent the opposite side of the aper-

ture, the width of any portion of the clamping arms being substantially greater than the thickness of the member; a bolt extending through the tubular portions; and a nut cooperating with the bolt to cause the arms to tightly embrace the shank, the bending of the arms taking place chiefly about the side of the shank opposite the bolt.

2. A clamp according to claim 1 in which the flat member is provided with lugs offset from the main portion of the member and adapted to provide clamping grips which bite into the shank of the timer housing when the arms of the clamp are drawn together, two of the lugs being each located adjacent the notch spacing the tubular portions and at least one other lug being located on the opposite side of the aperture.

In testimony whereof I hereto affix my signature.

FREDERICK C. KROEGER.
